(57) **CLAIM**

The ornamental design for a low profile pocket tool, as shown and described.

DESCRIPTION

FIG. 1 is a front elevation view of a first embodiment of the low profile pocket tool shown with an open blade.

FIG. 2 is a perspective view of a first embodiment of the low profile pocket tool.

FIG. 3 is a perspective view of a first embodiment of the low profile pocket tool shown with an open blade.

FIG. 4 is a top plan view of a first embodiment of the low profile pocket tool.

FIG. 5 is a bottom plan view of a first embodiment of the low profile pocket tool.

FIG. 6 is a front elevation view of a first embodiment of the low profile pocket tool.

FIG. 7 is a rear elevation view of a first embodiment of the low profile pocket tool.

FIG. 8 is a right side view of a first embodiment of the low profile pocket tool.

FIG. 9 is a left side view of a first embodiment of the low profile pocket tool.

FIG. 10 is a front elevation view of a second embodiment of the low profile pocket tool wherein a wolf's head is included as part of the claimed design. In all other respects, the second embodiment is the same as the first embodiment.

FIG. 11 is a rear elevation view of a second embodiment of the low profile pocket tool wherein a wolf's head is included as part of the claimed design. In all other respects, the second embodiment is the same as the first embodiment.

FIG. 12 is a front elevation view of a third embodiment of the low profile pocket tool wherein a box cutter is included as part of the claimed design. In all other respects, the third embodiment is the same as the first embodiment; and,

FIG. 13 is a rear elevation view of a third embodiment of the low profile pocket tool wherein a box cutter is included as part of the claimed design. In all other respects, the third embodiment is the same as the first embodiment.

The broken lines depict portions of the low profile pocket tool in which the design is embodied that are not considered part of the claimed design for the particular embodiments in which they appear.
